CAFTON

Lawrence W. Beaume, Monroe, Mich., assignor to
 River Raisin Paper Company, Monroe, Mich., a
 corporation of Michigan

Application July 8, 1937, Serial No. 152,598

6 Claims. (Cl. 229—27)

The present invention relates to cartons of the type which are formed from cardboard or other laminated paper material, and particularly to cartons of the type mentioned which are adapted to hold beverage bottles and the like. The cartons used for beverage bottles are subject to rough usage and are returned to the bottler and repeatedly reused. When filled with bottles containing a liquid, the contents of the carton are quite heavy and it is essential that the carton have sufficient strength to sustain the load even when the entire carton is lifted by means of a hand hole in one end wall thereof. This is necessary in view of the practice of truckers of picking up two filled cartons, one in each hand, by engaging with each hand a hand hole in the end of a carton. The use of laminated paper cartons for this purpose has become quite extensive in view of their low costs, but serious difficulties have been encountered in providing cartons of this type which are sufficiently strong to withstand the rough usage for any substantial length of time.

Accordingly, it is one of the principal objects of the present invention to provide a carton of the type mentioned which is simple in construction and so designed that it will readily withstand rough usage and particularly handling by a single hand hole in one end of the carton.

Another object of the invention is to provide a carton having a special hand hole positioned centrally within the carton for lifting the same when the cover flaps are open.

Another object of the invention is to provide a carton of the type mentioned which, when closed, will not admit light to the contents.

Other objects and advantages of the invention will become apparent from the following specification, the accompanying drawing, and the appended claims.

In the drawing:

Figure 1 is a perspective view showing the carton opened and with a portion of one end wall disassembled to show the mode of construction;

Fig. 2 is a section taken on the line 2—2 of Fig. 1;

Fig. 3 is a section taken on the line 3—3 of Fig. 2;

Fig. 4 is a sectional view corresponding to Fig. 3, but of a modified form of the invention; and

Fig. 5 is a fragmentary plan view taken on the line 5—5 of Fig. 4.

Referring particularly to Figs. 1 and 2 of the drawing, the main body portion of the carton

is preferably formed of a single sheet of laminated paper or cardboard provided with a plurality of parallel crease lines which divide the sheet of material into a top flap 10, a half top member 11, a side wall 12, a bottom wall 13, a side wall 14, a half top member 15, and a top flap 16. The side walls 12 and 14 are provided, respectively, with end flaps 17 and 18 and the bottom wall is provided with corresponding flaps 19. When the sheet of material is folded into the form shown, end walls 20 are secured to the flaps 17, 18, and 19 by any suitable means, such as staples 21, thus completing the main body portion of the carton. As shown best in Figures 1 and 2, it will be noted that the end walls 20 are also provided at their upper edges with a pair of flaps 22 and 24 for a purpose to be described hereinafter. The carton may be provided with the usual cross-partition members 26 and longitudinal partition members 27, which divide the box 20 into a plurality of compartments, each adapted to receive a single bottle or receptacle.

There is provided, in accordance with the present invention, a longitudinal partition member, indicated generally at 30, which extends longitudinally of the box midway of the sides 12 and 14. This partition member is preferably formed of a single sheet of laminated paper material and is folded along its upper edge to provide a pair of overlapping partition members 31 and 32. These partition members 31 and 32 are preferably secured together by any suitable means such as a staple 33, shown best in Figures 2 and 3. The ends of the partition member 31 are provided with a pair of flaps 35 and the ends of the partition member 32 are provided with similar flaps 36. These flaps are bent at right-angles to the partition 30 into the plane of the end walls 20, whereupon the flaps 22 and 24 on the top edges of the end walls are folded over the flaps 35 and 36 and secured by means of staples 38 to the flaps and the end walls proper. By this means, the partition 30 is fixedly secured to the end walls of the carton. The partition is formed of relatively heavy material and accordingly has substantial stiffness and strength. Hence, it forms a strong reinforcement for the entire box and particularly for the end walls.

The reinforcing action of the partition 30 is important in view of the fact that the end walls 50 are provided with the usual hand hole 39, by means of which the carton may be grasped and lifted. It should be noted that the hand hole is so arranged that it is located entirely within the area covered by the flaps 35 and 36 of the parti-

tion member 30 and that accordingly the hand hole is formed in a double thickness of material, thus greatly enhancing its strength. In addition, the flaps 22 and 24 on the top edges of the end 5 wall are of such length that when bent over the flaps 35 and 36, their extremities lie along the top edges of the hand hole 39, thus additionally reinforcing the end wall at this point. This arrangement gives a triple thickness of relatively 10 stiff, strong material above the hand hole, at which point the greatest load is applied. Accordingly, it is possible to lift a fully loaded carton with one hand by means of the hand hole provided in one end wall without injuring or 15 unduly straining the carton in any way.

In addition, it will be noted that there is provided in the partition member 30 an additional hand hole 46 intermediate the ends of the partition member. This hand hole 46 is useful for 20 lifting the carton at any time when the lid of the box is open. This may be required for purposes of inspection, or otherwise, at the time the cartons are loaded.

In forming the hand holes in the end walls of 25 the carton, it is possible to entirely remove the material of both the end wall and the overlapping portion of the flaps 35 and 36. However, it is preferable to leave the material of the flaps 35 and 36 partially connected to the flaps, as shown 30 best in Fig. 2, thus providing a pair of flaps 40 and 41 at each hand hole, which normally serve to close the hand hole and prevent the admission of light to the contents of the carton. This is particularly desirable when the carton is to 35 be used for transporting beer bottles, inasmuch as beer can only be kept well in the dark. As shown in the drawing, the flaps 40 and 41 are preferably hinged at the lower edge of the hand hole, but it is apparent that they may be hinged 40 at any other edge thereof. The material from which the partition 30, and therefore flaps 35 and 36, is made is of sufficient stiffness and resiliency to cause the flaps to swing back into 45 closing position after they have been displaced therefrom.

It should be noted that in the preferred form of the invention shown in Figs. 1, 2, and 3, that the top edge of the partition member 30 is spaced somewhat below the top edge of the end walls 20. 50 This is done in order to provide a small space 45 between the top flaps 10 and 16 and above the partition member 30 when the half top members are closed, as best shown in Fig. 3. This space 45 will permit the insertion of one or more fingers between the flaps 10 and 16 for the purpose of engaging and lifting the top of the box. It should be noted that the half top members 12 and 15, when in closed position, rest at their end edges upon the top of the end walls 20, thus 55 limiting downward movement of the half top members beyond the position shown in Fig. 3.

While the partition 30 is shown in Figs. 1, 2, and 3, as terminating just above the partition members 26 and 27, it is apparent that it may, if desired, extend all the way to the bottom of 60 the carton, thus replacing the central longitudinal portion 21. In that event, the partition member 30 would be provided with slots similar to the slots 47 in the central partition member 27 and the lower portion of partition member 70 30 would be received in similar slots in cross-portions 26. Such an arrangement is of advantage because it provides greater strength and, since the partition 30 is received in slots in partitions 26, the use of staples 33 can be avoided.

A modified form of the invention is shown in Figures 4 and 5, in which the partition member 30' is formed of sheet metal instead of a laminated paper material. The partition 30' is folded in the manner described with respect to the previous modification to provide a pair of partition members 31' and 32', each of which have their ends bent outwardly in the plane of the end walls 20' to form flaps 35' and 36'. It will be noted that when the partition member 30' is 10 formed of sheet metal that it may be made of substantially less height than in the previous modification of the invention and that accordingly, the lower edge thereof may conform to the upper edge of the hand hole 39' in the end 15 walls 20'. Accordingly, the flaps 35' and 36' assist in reinforcing the upper edge of the hand hole. In this modification of the invention, the flaps 22' and 24', on the end walls 20', are of greater length, with the result that when bent 20 inwardly over the flaps 35' and 36' they extend below the lower edges of the latter, in order that they may be secured to the end wall proper by means of staples 38'. It will be noted that the partition member 30' is not in itself secured 25 to the end walls but is held against displacement therefrom solely by means of the overlapping flaps 22' and 24' on the end walls 20'. The material which is removed from the end wall to form the hand hole 39' may, if desired, be only partially severed, leaving a flap 40' secured along the lower edge of the hand hole for maintaining the hand hole normally closed, as shown in Fig. 4.

It will further be noted that in the modification just described that the upper edge of the 35 partition 30' will lie substantially flush with the top edge of the end walls and that accordingly, there is no space corresponding to the space 45 shown in Fig. 3 in the prior form of the invention, by means of which the half top members 40 may be lifted. Accordingly, in this form of the invention, a pair of finger tabs 50 and 51 are partially cut from the half top members 11' and 15'. These finger tabs 50 and 51 are hinged to the half top members at 52 and 53 along the 45 crease lines between the top flaps and the half top members, as best shown in Fig. 5. Accordingly, the finger tabs may be depressed in order to provide an opening for engagement of a finger beneath the half top members in order to lift 50 the latter, but they will spring back and close the opening thereafter, thus preventing the entrance of light to the carton. In this form of the invention it is unnecessary to provide a separate hand hole in the partition member 30' as there 55 is sufficient room to engage the under side of the partition member.

While only two forms of the invention have been shown and described, it is apparent that variations in the construction are available within 60 the spirit of the foregoing specification, the accompanying drawing, and within the scope of the appended claims.

What is claimed is:

1. A cardboard carton having side walls, end 65 walls, and a bottom wall connected together to form a box structure, said end walls being provided with hand holes for lifting the carton, a cardboard reinforcing member extending longitudinally of the carton intermediate the side 70 walls, said cardboard reinforcing member having end portions bent into the plane of the end walls and secured thereto to reinforce the latter, said end portions overlying said hand holes and being provided with corresponding hand- 75

receiving openings whereby the end portions reinforce the hand holes in the end walls.

2. A cardboard carton having side walls, end walls, and a bottom wall connected together to form a box structure, a pair of partition members positioned face-to-face and extending longitudinally of the carton intermediate the side walls in parallel vertical planes, the ends of said partition members being bent in opposite directions

10 into the plane of the end walls, said end walls being provided with hand holes, flaps on the upper edges of said end walls folded into the carton and into overlapping relation to said end portions of said members, and means for securing said last flaps to said end walls below the top edges thereof.

3. A cardboard carton having side walls, end walls, and a bottom wall connected together to form a box structure, a pair of partition members positioned face-to-face and extending longitudinally of the carton intermediate the side walls in parallel vertical planes, the ends of said partition members being bent in opposite directions into the plane of the end walls, said end walls 20 being provided with hand holes, flaps on the upper edges of said end walls folded into the carton and into overlapping relation to said end portions of said members, and means for securing said last flaps to said end walls below the top edges thereof, the extremities of said flaps being located along the upper edge of said hand holes to reinforce the same.

4. A cardboard carton having side walls, end walls, and a bottom wall connected together to 35 form a box structure, a pair of partition members positioned face-to-face and extending longitudinally of the carton intermediate the side walls

in parallel vertical planes, the ends of said partition members being bent in opposite directions into the plane of the end walls, said end walls being provided with hand holes, and means for securing said last-mentioned portions of the end 5 members to the end walls adjacent said hand holes, said partition members being formed from a single sheet of material and being joined at their upper edges.

5. A cardboard carton having side walls, end 10 walls, and a bottom wall connected together to form a box structure, said end walls being provided with hand holes for lifting the carton, a reinforcing member extending longitudinally of the carton intermediate the side walls and being 15 secured to the end walls to reinforce the same, and a hand hole in said reinforcing member located intermediate its ends.

6. A cardboard carton having side walls, end walls, and a bottom wall connected together to 20 form a box structure, a pair of partition members positioned face-to-face and extending longitudinally of the carton intermediate the side walls in parallel vertical planes, the ends of said partition members being bent in opposite directions 25 into the plane of the end walls, said end walls being provided with hand holes, flaps on the upper edges of said end walls folded into the carton and into overlapping relation to said end portions of said members, and means for securing 30 said last flaps to said end walls below the top edge thereof, the lower edges of said end portions of said partition members being located along the upper edge of said hand holes to reinforce the same.
